 County, Mass., a corporation of Massachusetts

Application September 27, 1950, Serial No. 187,016

4 Claims. (Cl. 22—73)

1

This invention relates to the production of metals and more particularly to the melting and casting of metals in a vacuum. One of the basic problems in vacuum melting and casting is the long time requirement imposed on batch operation and the consequent effect on production cost. In particular, when one metal or alloy is being melted or cast in quantity, it is desired that a maximum number of melts be obtained from one crucible. To achieve this purpose there are several important features of the operation to be considered. The first of these is the minimizing of oxidized residue created between runs when a hot crucible containing some residual metal is exposed to air. The second consideration is the avoidance of thermal stresses in the crucible so as to prevent cracks which greatly shorten the crucible life. Both of these difficulties can be avoided by keeping the melting chamber continuously at a low atmospheric pressure to avoid oxidation of the crucible or its contents, and by making melts in rapid succession so as to avoid undue cooling of the crucible between melts.

Accordingly, it is a principal object of the present invention to provide a vacuum melting and casting furnace which can be operated in a semi-continuous manner so as to avoid oxidation of the crucible or its contents, and which can be so handled that cooling of the crucible between melts is substantially avoided.

Still another object of the invention is to provide such a melting and casting furnace which may be charged with rondelles, flake, lump, shot, powder, pig, or various types of scrap, and from which ingots or castings may be discharged without necessitating venting to atmosphere of the crucible portion of the furnace.

Still another object of the invention is to provide a furnace having a high production rate for a given crucible capacity and power input.

Still another object of the invention is to provide such a melting and casting furnace which is equally adapted for making cast shapes or for the production of ingots.

Still another object of the invention is to provide a melting and casting furnace capable of producing high purity metals at low cost.

Other objects of the invention will in part be obvious and will in part appear hereinafter.

The invention accordingly comprises the apparatus possessing the construction, combination of elements and arrangement of parts which are exemplified in the following detailed disclosure, and the scope of the application of which will be indicated in the claims.

For a fuller understanding of the nature and objects of the invention, reference should be had to the following detailed description taken in connection with the accompanying drawings wherein:

2

Fig. 1 is a diagrammatic, schematic, elevation view of one preferred form of the invention;

Fig. 2 is a plan view of the furnace of Fig. 1 with parts thereof broken away for better illustration of the interior of the furnace;

Fig. 3 is a sectional view along the line 3—3 of Fig. 1;

Fig. 4 is an enlarged, fragmentary, sectional view along the line 4—4 of Fig. 2;

Fig. 5 is a fragmentary, sectional view along the line 5—5 of Fig. 4; and

Fig. 6 is an enlarged, fragmentary, sectional view along the line 6—6 of Fig. 3.

In general, the present invention relates to a vacuum furnace for melting and casting metal under a vacuum for the purposes of making high-purity ingots, castings, or alloys from initially high-purity metals, or for purifying metals as a result of melting thereof under vacuum and subsequently forming castings or ingots of the purified melts. The vacuum furnace of the present invention comprises a vacuum-tight furnace chamber having a metal-melting crucible therein, this portion of the furnace being provided with a means for evacuating this furnace chamber to a low pressure on the order of 1-5 microns Hg abs. or less. The furnace also includes a second vacuum chamber, a means for evacuating this second vacuum chamber, and a means for introducing metal to be melted into the second vacuum chamber, this last-named means including a vacuum-tight closure. Between these two chambers there is provided a means, including a second vacuum-tight closure, for transferring metal to be melted from the second vacuum chamber into the crucible positioned in the furnace chamber. The furnace chamber includes electrical means for heating the metal in the crucible to a temperature above its melting point, and a means for discharging the molten metal from the crucible into a mold therefor. The furnace is also provided with a means constituting a vacuum-tight closure for isolating the mold from the furnace chamber after the molten metal has been poured into the mold, and means including another vacuum-tight closure for removal of the isolated mold from the furnace.

In a preferred form of the invention illustrated in the accompanying drawings, the mold is positioned in, or forms a part of, a third vacuum-tight chamber which can be isolated from the furnace chamber to permit removal and replacement of the mold.

Referring now more particularly to Figs. 1, 2 and 3, wherein like numbers refer to like elements of these and the other figures, there is shown one preferred form of the invention wherein there is provided a vacuum-tight furnace chamber 10 arranged to be evacuated through a pipe 11 (Fig. 2) which is connected to a suitable

vacuum pumping system not shown. For feeding metal to be melted there is included a second vacuum-tight chamber 12 which can be evacuated through a pipe 13 which is also connected to a suitable vacuum pumping system. For casting an ingot there is provided a third vacuum-tight chamber 14, a portion of which is formed by the ingot mold itself, this vacuum-tight chamber 14 being arranged to be evacuated through a third pipe 15 connected to a suitable vacuum pumping system. Positioned within the furnace chamber 10 is a crucible, generally indicated at 16, which is arranged to be heated by an electrical heating means, such as an induction coil 18.

For transferring metal to be melted from the feeding chamber 12 to the furnace chamber 10 there is provided a transfer means which includes a bucket 20. A trough 22 is positioned so as to transfer molten metal from the crucible 16 to the casting chamber 14. A plurality of vacuum-tight closures or valves are provided in connection with the above furnace, there being a first such vacuum-tight closure 24 associated with the feeding chamber 12 through which metal may be introduced into this feeding chamber 12. Between the feeding chamber 12 and the furnace chamber 10 is a second vacuum-tight closure 26, while between the furnace chamber 10 and the casting chamber 14 is a third vacuum-tight closure 28. A fourth vacuum-tight closure 30 permits removal of the ingot from the casting chamber 14.

Melting section

Referring now more specifically to the details of the elements outlined briefly above, the furnace chamber 10, as shown best in Fig. 3, comprises a removable cover 32 through which access to the interior parts may be had for repair or replacement. A sight glass 34 is preferably provided in the cover 32 so that the melting operation may be observed. A water-cooled stirring rod 36 is also preferably provided for agitating the melt or breaking down any "bridges" which may form at the top of the melt. The furnace chamber 10 includes a double wall 37 which is arranged to be cooled by circulating water therethrough from suitable connections not shown. The crucible assembly, generally indicated at 16, comprises a refractory pot 38 supported by a carriage 40, this carriage 40 being pivotally mounted on bearings 42 supported by a bracket 44 attached to the wall 37 of the furnace chamber 10. The heating means 18 comprises a plurality of turns of copper tubing 46, each turn being surrounded by insulating material such as a composite lamination of phenolic resin and glass tape. The two ends of the copper tubing 46 extend through an insulating block 48 associated with the crucible carriage 40. These two ends of the tubing 46 are connected to insulated flexible water-cooling lines (not shown). The electrical connection to the portions of the tubing 46, which pass through the insulating block 48, are shown in more detail in Fig. 6.

As can be seen in this Fig. 6 these terminal portions of the tubing 46 are adapted to be energized from a coaxial element 50 having a pair of electrical contacts 52 thereon. Each contact 52 makes an electrical connection with a conductor element 54 which is, in turn, in electrical connection with one end of the tubing 46. For shielding the connection between the elements 52 and 54 there is provided a compressible gasket 56 around each contact 52. This arrangement has been found to be particularly suitable for

65

70

preventing any ionizing discharge at very low free air pressures in the system and at voltages in excess of 200 volts. The coaxial element 50 is preferably rigid and comprises an insulating block 58 separating the two contacts 52 and also supporting the outer ends of two coaxial tubes 60 and 62, these two tubes 60 and 62 serving as the two current leads. The outer tube 62 is preferably grounded as indicated at 63, to prevent ionization discharge between the outer tube 62 and the furnace walls 37 or the crucible support 40. This rigid assembly is supported by a flange 63 which is clamped, by means of the arrangement generally indicated at 64, in vacuum-tight relationship to a flange 65 supported on the wall 37 of the furnace chamber. Suitable current supply and cooling water connections are provided for the rigid coaxial element 50.

For pouring the melt from the crucible there is provided a lip 66 (Fig. 3) associated with the crucible pot 38 and a tilting mechanism, including a pair of chains 68 engaging a pair of sprockets 70. These sprockets 70 are mounted on a shaft 72 which passes through a vacuum-tight seal 74 (Fig. 2) to the exterior of the furnace chamber 10. On the outer end of the shaft 72 there is provided a suitable mechanical system, such as a handle 76 for turning the shaft. A pair of weights 78 (Fig. 3) attached to the ends of chains 68 assist in counterbalancing the weight of the loaded crucible. In a preferred form of the invention the lip 66 associated with the crucible pot 38 is positioned so that it is about on the axis of bearings 42. By means of this arrangement the lip remains essentially stationary during the tilting of the crucible and thus remains over the upper end of the trough 22.

The crucible 38 is also preferably provided with a cover 80 for preventing spattering of materials from the crucible during the melting, and also for preventing undue radiation heat loss from the melt. This cover 80 is carried by fingers 82 supported on a rod 84 (Fig. 2). Rod 84 preferably includes an electrical insulation section so that the cover 80 is insulated from the remainder of the apparatus. Rod 84 is arranged to be swung around a pivot 86 and also to be rotated around its own axis. The pivoting movement of the rod 84 is accomplished by means of an operating connection 88 associated with an operating means such as handle 90 extending to the exterior of the furnace. During movement of the crucible cover 80 it is first rotated about the axis of pivot 86 by operating the handle 90. As the crucible cover 80 approaches the dotted line position of Fig. 2 a detent 85 carried by the arm 84 engages another detent 87 to cause the arm 84 to rotate around its axis, thus moving the crucible cover 80 into the position shown in dotted lines in Fig. 2 to prevent radiant heating of the crucible assembly by the hot cover. The cover 80 is shown in this removed position in Fig. 3.

Metal feeding section

The mechanism for feeding the metal to be melted is shown in the greatest detail in Figs. 4 and 5 wherein the metal-transferring bucket 20 is shown as being supported by a rod 100 which is pivotally carried by a pair of brackets 102 connected together by clamp 103 (Fig. 5). Brackets 102 have rollers 104 at their upper end, these rollers 104 being supported by track 106 which, except for short gaps under valve 24 and within the vacuum-tight valve 26, extends to the interior of the furnace chamber 10. The left-hand side

of the supporting rod 100 is provided with a detent 108 adapted to be engaged by another detent 109 (see Fig. 2) associated with a turning mechanism 110 positioned on the far side of the furnace chamber 10. On the right-hand side of the bucket 20 (Fig. 4) there is provided a rack 112 connected to one of the brackets 102, this rack 112 being positioned so as to be engaged by a pinion 114. Pinion 114 is rotated by a suitable operating means, such as a handle 115 (see Fig. 2), positioned exteriorly of the feeding chamber 12. Rack 112 is held in engagement with the pinion 114 by means such as a roller 116. For providing space for movement of the rack 112 there is included an extension 118 for the chamber 12, this extension being shown in the form of a long tube closed at its outer end.

The vacuum-tight valve 24 through which the loading of the bucket 20 is achieved comprises an opening 120 in feeding chamber 12, this opening being normally closed by a gasketed cover 122. Cover 122 is preferably supported by a yoke 124, this yoke carrying an operating handle 126 and being pivotally mounted at 128 to permit swinging of the cover 122 clear of the opening 120. For steadyng the bucket 20, during passage of roller 104 across the gap in track 106 under valve 24, a pair of guide rods 130 are secured to the inside of chamber 12. Valve 26 is not shown in detail but may be essentially similar to the valve 28 shown in more detail in Fig. 3 and discussed hereinafter.

Casting section

The casting section of the furnace is shown best in Fig. 3 wherein there is preferably provided an extension 140 for the furnace chamber 10. This extension 140 has an opening 142 at the bottom thereof above which is located a hole 141 in the lower end of the trough 22. Opening 142 is normally closed by the vacuum-tight valve 28, this valve 28 preferably comprising a closure plate 144 which is carried by a rod 146. Rod 146 is preferably connected to the closure plate 144 by means of cam sections 148, which permit tight closure of the valve upon rotation of the rod 146 by means of handle 147. Rod 146 is thus able to move the closure plate 144 both translationally across the opening 142 and also towards the opening 142. The valve 28 also preferably includes a water-cooled radiation shield 150 mounted on a shaft 152, the purpose of the radiation shield 150 being to prevent radiation of heat from the cast metal in the mold 14, thereby preventing warping and seizing of the closure plate 144 and deterioration of sealing gaskets due to overheating thereof. The trough 22 is preferably heated to a suitably high temperature by a radiant heater 151 so that the molten metal will not be chilled to its solidification point during flow down the trough 22.

The casting chamber 14 is shown in one preferred form as comprising a double-wall ingot mold 154 having water inlet and outlet connections 156. The ingot mold is preferably provided with a flange 158 at its upper end, this flange forming the vacuum-tight closure 30 with a matching flange 159 carried by the valve 28. A sight glass 160 is preferably located at the top of extension 140 to permit viewing of the mold during the casting of the melt therein. A sight glass cleaner is schematically indicated at 162, this cleaner being arranged to scrape condensed metal vapors from the under surface of the sight glass 160. A similar cleaner can be provided for the sight glass 34 if desired.

Vacuum system

The vacuum system comprises a number of separate vacuum pumping lines which lead from the various portions of the apparatus to suitable vacuum pumps not shown. As best seen in Fig. 1 feeding chamber 12 is provided with a vacuum pumping line 13 and a vacuum cutoff valve 170 for closing this line 13 when the vacuum-tight closure 24 is to be opened. For releasing the vacuum in the chamber 12, to permit opening of the closure 24, there is provided a vent valve 172 which, when opened, permits atmospheric pressure to enter chamber 12. A similar arrangement is provided for the casting chamber 14 wherein the vacuum pumping line 15 is provided with a vacuum cutoff valve 174 and an atmospheric vent valve 176. The pipe 15 also includes a third valve 178 which controls the flow of gas from a pipe 180 leading to a supply of inert gas such as argon and the like. This inert gas can be at any desired pressure such as 15 lbs. per square inch abs.

Operation of the furnace

In the operation of the furnace described above assume that a crucible is positioned in the furnace to start melting a large batch of metal, this crucible being preferably filled with the metal to be melted. As the operating cycle commences cover 32 is placed on the furnace chamber 10 and initial pumpdown of the furnace is accomplished. For this initial pumpdown the atmospheric vent valves 172 and 176 are closed. The vacuum valves 170 and 174, inert-gas valve 178, and closure 24 may be closed, in which case the whole system may be pumped down through the pipe 11 associated with the main furnace chamber 10, the valves 26 and 28 being left open to permit pumpdown of all three of the vacuum chambers. During this pumpdown it is sometimes desirable to energize the induction heating means so as to assist in the outgassing of the crucible pot 38. When the furnace interior has been pumped down to a low pressure, on the order of .001 mm. Hg abs., heating of the metal in the crucible pot 38 may be continued until it is thoroughly melted, and the degassing and any necessary metallurgical reactions have been carried out. Valve 28 is then opened if it is not already open, and cooling water is passed between the double walls of the mold 154. Crucible cover 80 is then rotated from the position shown in full lines in Fig. 2 to the position shown in full lines in Fig. 3. After cutting off electrical power to the coil 18, the crucible pot 38 is tilted around the axis of the bearings 42 by rotating the operating handle 76 (Fig. 2) so as to rotate sprockets 70, thus moving the chain 68 connected to the crucible support 40. The melt in the pot 38 flows over the lip 66 as the crucible tilts. This melt falls into the upper end of the trough 22, travels down the heated trough and out through the hole 141 at the bottom end thereof. From hole 141, the melt falls into the water-cooled mold 154, this mold being cooled, as mentioned previously, so that the hot metal does not burn through the walls of the mold or bond to the walls thereof. When the crucible has been emptied it is returned to the vertical position shown in Fig. 3, and the valves 28 and 26 may then be closed to isolate the three main chambers. In some cases it is desirable to maintain the valve 28 open so that gases liberated during the solidification of the cast melt can be removed by the vacuum pump associated with pipe 11 leading to the furnace chamber. This is particularly

desirable when the vacuum pump connected to pipe 11 has a large capacity as compared to the vacuum pump connected to the pipe 15.

The valve 24 is then opened, after venting the feeding chamber 12 by means of the vent valve 172. A fresh supply of metal to be melted is inserted in the bucket 20, the valve 24 is closed, the vent valve 172 is closed, and the vacuum valve 170 is opened to permit pumping down the feeding chamber 12 to a pressure on the order of 50 microns or less. The valve 25 is then opened, thus permitting equalization of the pressure between the feeding chamber 12 and the furnace chamber 10. The slight difference in the pressure between the interiors of the chambers 12 and 10 is not sufficient to cause any great increase of the pressure in furnace chamber 10 due to the much greater volume of the latter, this pressure increase being on the order of a very few microns. If desired, an addition to the pumping system of the feeding chamber 12 can completely eliminate even this small effect.

The operating handle 115, associated with the pinion 114, is then rotated, thus advancing the rack 112, and the bucket 20 connected thereto, from the chamber 12 into the chamber 10. This movement is continued until the bucket 20 is over the crucible pot 38, and the detent 108 on the outer end of the rod 100 is in engagement with the corresponding detent 109 associated with the turning mechanism 110 (Fig. 2). The turning mechanism 110 is then rotated to cause a tilting of the bucket 20 so that its contents are dumped into crucible pot 38. The bucket 20 is then righted and returned to the chamber 12. If the load of metal in the bucket 20 is not sufficient to fill the crucible pot 38, the valve 25 is immediately closed. The vent valve 172 is opened, as is the closure 24, and the bucket 20 is refilled. Closure 24 is then replaced, vent valve 172 is closed, and the vacuum pumping valve 170 is opened. When feeding chamber 12 has again been evacuated the loading operation is repeated by again opening the valve 25 and advancing the bucket to a position over the crucible pot 38. Such a cycle consumes on the order of 3-5 minutes, without interruption of the melting operation, which can be carried out simultaneously.

After the ingot cast in the mold 14 has been cooled sufficiently, the vacuum valve 25 is closed and vent valve 176 is opened. The vacuum-tight connection 39 between the two flanges 153 and 159 is then broken and mold 154 is removed. The cast ingot can then be removed from the mold 154 or a new mold can be positioned in place of the old mold. When the new mold, or emptied mold, has been secured in position, the vent valve 176 is closed and vacuum valve 174 is opened, thus allowing the vacuum casting chamber 14 to be evacuated to a suitable low pressure. At the desired time before the next melt is to be cast, valve 25 is opened and the casting operation is repeated.

In many cases it is desired to solidify the ingot or casting under inert gas pressure. When this is to be achieved the valve 25 is closed immediately after casting of the melt, the vacuum pumping valve 174 is closed, and the valve 173 leading to the inert gas supply is opened thus allowing any desired pressure of inert gas to be created above the surface of the solidifying casting. When a complex alloy is being cast, for instance, it has been found that an atmospheric pressure of argon gives considerably improved ingots, by reason of better filling of interden-

75
8
dritic shrinkage cavities by molten metal under the increased hydrostatic pressure.

In many cases it is desirable to employ a furnace of the type described above for making precision castings. Certain such castings are particularly desirable when made under vacuum conditions since they are free of voids, are very dense, and have superior mechanical and electrical properties. In order to achieve such precision casting the vacuum casting chamber 14 is modified to hold a precision casting mold, the mold being positioned so that it can be filled by metal pouring through hole 141 in the trough 22. In other respects the arrangement of elements and the operation of the device may be identical to that previously discussed.

In the preferred type of furnace illustrated in the drawings the various structural portions thereof are made of austenitic stainless steel or other nonmagnetic steel, while the crucible 38 is made of a high-purity refractory such as magnesia or graphite, as required by the material to be melted. The trough 22 is preferably formed of magnesia or alumina. The crucible is preferably packed into the copper coil 46 by means of a magnesia ramming mix. The various insulating blocks such as 48 and 58, and the insulation (not shown) in the arm 34 may comprise synthane. As mentioned previously the coil 46 is preferably wrapped with glass tape over a phenolic resin to give an arc-free coil assembly which can be operated at 3000 cycles per second and with 400 volts and up to 100 kilowatts power input.

Since certain changes may be made in the above apparatus without departing from the scope of the invention herein involved, it is intended that all matter contained in the above description, or shown in the accompanying drawings, shall be interpreted as illustrative and not in a limiting sense.

What is claimed is:

1. A semi-continuous furnace for melting and casting a metal, alloy or the like under a vacuum, said furnace comprising a vacuum-tight furnace chamber, a metal-melting crucible in said furnace chamber, means for evacuating said furnace chamber, means forming a second vacuum-tight chamber communicating with said furnace chamber and laterally displaced from said crucible, means for evacuating said second vacuum-tight chamber, means for introducing a solid metal to be melted into said second vacuum-tight chamber, said introducing means including a vacuum-tight closure, a second vacuum-tight closure positioned between said furnace chamber and said second vacuum-tight chamber for isolating said two vacuum-tight chambers, a movable bucket for transferring said metal from said second vacuum-tight chamber to said furnace chamber, means for positioning said bucket so that the contents thereof can be poured into said crucible, electrical means for heating said metal in said crucible to a temperature above its melting point, means for discharging molten metal from said crucible into a mold therefor, means constituting a vacuum-tight closure for isolating said mold from said furnace chamber after pouring said molten metal into said mold, and means including a vacuum-tight closure for removal of said isolated mold from said furnace.

2. A semi-continuous furnace for melting and casting a metal, alloy or the like under a vacuum, said furnace comprising a vacuum-tight furnace chamber, a metal-melting crucible in said furnace

chamber, means for evacuating said furnace chamber, means forming a second vacuum-tight chamber communicating with said furnace chamber, means for evacuating said second vacuum-tight chamber, means for introducing a solid metal to be melted into said second vacuum-tight chamber, said introducing means including a vacuum-tight closure, a second vacuum-tight closure positioned between said furnace chamber and said second vacuum-tight chamber for isolating said two vacuum-tight chambers, means for transferring said solid metal from said second vacuum-tight chamber to said crucible, electrical means for heating said metal in said crucible to a temperature above its melting point, said crucible including a pouring lip and means for tilting said crucible around a horizontal axis which substantially coincides with said pouring lip, a trough for transferring molten metal from said crucible to a mold, one end of said trough being positioned under said pouring lip and the other end of said trough being over said mold, a vacuum-tight valve between said mold and the end of said trough for isolating said mold from said furnace chamber, and a radiation shield positionable between said mold and said last-named vacuum-tight valve.

3. A semi-continuous furnace for melting and casting a metal, alloy or the like under a vacuum, said furnace comprising a vacuum-tight furnace chamber, a metal-melting crucible in said furnace chamber, means for evacuating said furnace chamber, means forming a second vacuum-tight chamber communicating with said furnace chamber, means for evacuating said second vacuum-tight chamber, means for introducing a solid metal to be melted into said vacuum-tight chamber, said introducing means including a vacuum-tight closure, a second vacuum-tight closure positioned between said furnace chamber and said second vacuum-tight chamber for isolating said two vacuum-tight chambers, means positionable in both of said vacuum-tight chambers for transferring said solid metal from said second vacuum-tight chamber to said crucible, electrical means for heating said metal in said crucible to a temperature above its melting point, means for discharging molten metal in said crucible into a mold therefor, means constituting a vacuum-tight closure for isolating said mold from said furnace chamber after pouring said molten metal into said mold, and means including a vacuum-tight closure for removal of said isolated mold from said furnace.

4. A semi-continuous furnace for melting and casting a metal, alloy or the like under a vacuum, said furnace comprising a vacuum-tight furnace chamber, a metal-melting crucible in said furnace chamber, means for evacuating said furnace chamber, means forming a second vacuum-tight chamber communicating with said furnace chamber, means for evacuating said second vacuum-tight chamber, means for introducing a solid metal to be melted into said second vacuum-tight chamber, said introducing means including a vacuum-tight closure, a second vacuum-tight closure positioned between said furnace chamber and said second vacuum-tight chamber for isolating said two vacuum-tight chambers, means for transferring said solid metal from said second vacuum-tight chamber to said crucible, electrical means for heating said metal in said crucible to a temperature above its melting point, means for tilting said crucible around a horizontal axis to pour a melt from said crucible to a mold, said electrical means including a first electrical contact means fixed with respect to said crucible and a second electrical contact means fixed with respect to said furnace, said two electrical contact means being in engagement when said crucible is in melting position and being out of engagement when said crucible is in pouring position, means constituting a vacuum-tight closure for isolating said mold from said furnace chamber after pouring said molten metal into said mold, and means including a vacuum-tight closure for removal of said isolated mold from said furnace.
